BERNARD A. MALKIN, OF LACHINE, QUEBEC, CANADA.

DRIVE FOR PAPER-DRYING MACHINES AND THE LIKE.

Application filed November 27, 1925. Serial No. 71,809.

This invention relates to new and useful improvements in paper making machines and particularly to the main driving gear for paper drying machines and the object of the invention is to provide a main driving gear of the class stated which will be highly efficient in operation and which will avoid the accumulative inefficiency of the long train of gears in machines of this class in use at the present time.

Another object of the invention is to provide a gear of the class stated, which will allow drying machines to be operated at high speeds by reducing the pitch line speeds of the gears as usually arranged in machines of this class at present in use.

A further object is to provide a driving mechanism of the class stated in which all the gears will run in oil tight gear cases, to reduce the wear in the gears of the machine and also to reduce the noise of the working of the machine to a minimum.

A still further object is to provide a totally enclosed drive of the class stated which will provide an absolute centering means between each pair of rolls to ensure proper meshing of the gears, a feature which is not provided for in driers as at present constructed.

Other advantages will be apparent to persons familiar with this art from the following description.

In my invention, I provide a longitudinal driving shaft, extending from end to end of the machine, and driven from a source (not shown). Driven by bevel wheels and bevel pinions are the toothed pinions, which mesh with toothed wheels, secured to the ends of the drier roll shafts. The drier roll gears are arranged in units, each unit being enclosed in oil tight gear cases and adapted to drive a pair of rolls, preferably one upper and one lower roll. The tooth wheels run in oil and the casings are so arranged that a perfect circulation of the lubricant is obtained when the machine is in operation.

In the drawings which illustrate certain embodiments of my invention.

Figure 1 is a side elevation of part of a drying machine showing my improved driving mechanism.

Figure 2 is a side elevation of part of a paper making machine showing one modified form of drive from that shown in Figure 1.

Figure 3 is an enlarged side elevation of part of the machine with parts cut or broken to show the drive more clearly.

Figure 4 is a sectional elevation of one of the roll driving gears taken on the line 4—4 Figure 3.

Figure 5 is a sectional elevation taken on the line 5—5 Figure 3.

Referring more particularly to the drawings, 11 designates the frame of a paper making machine, upon which are mounted in staggered relationship, the upper and lower drier rolls 12 and 13. Between each pair of upper and lower rolls and rotatably mounted in suitable bearings 14, are the guide rolls 15, which form a means for guiding the drier felts through the machine. The felts are mounted in the usual manner, that is over one section of one of the rolls, under the guide rolls and over the adjacent drier rolls. The paper sheet travels through the machine between the felts and the drier rolls, that is over an upper and then under a lower roll as it passes from one end of the machine to the other. This construction is practically standard construction in this type of machine and is well known in this art. This invention lies in the means used for driving the rolls and also differs from my prior application Serial No. 32,404, filed on May 23rd, 1925, in that a combined bevel and spur wheel is used instead of the bevel and worm gear drive used in the construction detailed in said prior application.

The drier roll spindles 16 extend beyond the bearings 17, supporting the rolls and secured in any suitable manner to its spindles are the toothed gear wheels 18, which mesh with toothed gear pinions 19, rotatably mounted on spindles 20, secured to the casting 21, hereinafter described. The bore of the hubs 22, are made slightly larger in diameter than the spindles and are formed to ride on a double conical roller bearing 23, held in place on said spindle by any suitable means, such as the pin and washer 24 and shoulder 25, illustrated in Figure 4. Secured to the side of the toothed gear pinions in any suitable manner, are the bevel tooth gear wheels 26. In Figure 4, I have shown the webs 27 of the tooth pinions positioned to one side and the wheels 26 secured thereto by bolts, but this may be altered to suit working conditions and existing material as required.

Extending for the full length of the machine and positioned between the upper and lower sets of rolls, is the main driving shaft 27, to which are secured the tooth bevel pinions 28, in such a manner as to mesh with the bevel toothed wheels 26. The outer face 29 of the hubs or bosses 30 of the pinions, contact with the faces 31 of the bearings 32, so that bending of the longitudinal shaft 27 is reduced to a minimum. The bearings are made of the split type, so that the caps 33 may be readily removed for erecting or dismantling the machine. Each pair of adjacent upper and lower drier rolls are mounted in suitable gear cases 34, which are made oil tight so that a perfect circulation of lubricant is maintained within the casing, by rotation of the gears. The casings may be made in sections to facilitate inspection and repairs to the machine. In Figure 4, I have shown in detail part of one of the casings, the back portion 35 of which is secured to one upper and one lower roller support bearing and is so formed that the bearings 32 for the longitudinal shaft 25 and bearings 36 for the spindles 20, are formed by casting them integral with the portion 35. As will be seen from such construction, that once the bearings in the casing are machined, all parts which gear with one another will mesh properly. Covers 37 may be secured to the portion 35 by any suitable means, to enclose the bevel toothed wheels and pinions and also the toothed gear pinions 19. Suitable covers 38, may be provided 30 for the toothed gear wheels and may be attached to the rest of the casing in any suitable manner. The covers 38 may be formed with apertures 39, which fit over the roll supporting spindles and suitable packings 40 may be placed in grooves 41 to prevent oil from leaking through the casing between the roll spindle and the walls of the apertures. Suitable sealing means (not shown), may be placed at the ends 42 of the casings and oil 45 thrower rings 43 may be formed on the longitudinal shaft between its supporting bearings within the casing to maintain the circulation of oil while the shaft is rotating. The above is made suitable for self-lubrication, but 50 by connecting the casing to a source of oil supply under pressure, an even more even distribution of lubricant may be obtained. The foregoing description relates to the type of drive shown in Figure 1 and detailed in Figures 3, 4 and 5. In the modified type of drive shown in Figure 2 only one set of bevels, namely one bevel tooth wheel 45 and one bevel toothed pinion 46 are used in each casing, but an idler toothed wheel 47 is used 55 as an extra unit to reverse the motion of the upper drier rolls. In Figure 2 the idlers are shown between the toothed gear wheels driving the upper rolls and the toothed gear pinions secured in any suitable manner to the 60 toothed bevel pinions 46 and may be con-

structed in a similar manner to that shown in Figure 4. All other parts of the mechanism may be made in a similar manner to that shown in Figure 1. Suitable couplings 48 may be used for coupling the sections of the 70 longitudinal shaft together and a toothed pinion or wheel 49 may be mounted approximately in the longitudinal centre of the shaft to gear with the driving mechanism such as a motor pinion, (not shown).

75 Modifications may be made without departing from the spirit of the invention.

In operation the drier rolls rotate in the manner shown by the arrows and the paper travels from left to right of the machine. As 80 will be seen the upper rolls rotate in the opposite direction to the lower rolls and this necessitates making provision for driving the roller gear wheels from different pinions when only one main driving shaft is used. 85 This is accomplished in the machine shown in Figure 1, by securing appositely disposed bevel pinions in each casing, one to drive the upper rollers and one to drive the lower rolls through the tooth pinion and wheel drive. 90 In Figure 2 a similar result is obtained by using only one bevel toothed wheel and pinion and using an idler to rotate the upper roll in the opposite direction. The gears being mounted in independent cases containing a 95 set of gears to drive an upper and a lower roll ensure that the gears will mesh properly, as this will be set in the making of the casings. The gears all run in oil tight casings 100 and are therefore subjected to a proper source of lubrication which tends to lengthen the life of the contacting parts, as well as forming a means for reducing the noise of the working of the machine to a minimum, and also prevents oil from falling or being thrown on to 105 the sheet of paper being dried.

This arrangement of gears also reduces the accumulative inefficiency of the spur drive usually employed in machines of this class, and therefore requires less power to drive 110 it when compared with machines as at present constructed.

Having thus described my invention, what I claim is:

1. In a paper making machine, a frame, 115 a plurality of upper and lower drier rolls secured to spindles rotatably mounted on said frame, toothed gear wheels secured to extensions of said spindles, toothed gear pinions meshing with the wheels and rotatably mounted on spindles secured to suitable bearings, a main driving shaft, extending the full length of the machine, bevel-toothed wheels secured to said pinions and bevel toothed pinions mounted on the shaft 120 and meshing with the bevel wheels to form a driving connection between the shaft and the toothed pinions.

2. In a paper making machine having upper and lower rolls rotatably mounted in 130

- staggered relationship on a main frame, a longitudinally disposed main driving shaft extending the full length of the machine between the upper and lower rolls, toothed gear wheels and pinions for driving said rolls, bevel toothed wheels and pinions forming a driving connection between the main shaft and the toothed pinions and casings surrounding the gears required to operate the adjacent upper and lower rolls.
3. In a paper making machine have a plurality of upper and lower rolls rotatably mounted in staggered relationship on a frame, a main driving shaft extending the full length of the machine between the upper and lower rolls, spur and bevel toothed gear wheels forming a driving connection between the main driving shaft and the drier rolls, and oil tight casings surround each set of gearing driving one upper and one lower roll.
4. In a paper making machine having a plurality of upper and lower rolls rotatably mounted in staggered relationship on spindles in suitable bearings formed in a frame, a main driving shaft extending in the longitudinal direction of the machine from end to end thereof and between the upper and lower rolls driving gear which includes spur tooth gear wheels mounted on extensions to the roll spindles, spindles secured to the casings, spur toothed gear wheels rotatably mounted on said spindles and meshing with the wheels, bevel toothed gear wheels adapted to rotate said pinions and bevel toothed gear pinions mounted on said shaft and meshing with the bevel toothed wheels.
5. A paper making machine according to claim 4 having the casings secured to the upper and lower roll bearing and oil tight covers centering the gearing between the roll spindles and the longitudinal driving shaft.
6. A paper making machine having upper and lower rolls secured to spindles mounted in bearings in staggered relationship in a frame, extension to said spindles projecting beyond the frame, gear casing between each pair of adjacent upper and lower rolls, a main driving shaft rotatably mounted in bearings in the casing and extending from end to end of the machine, spur toothed wheels on said spindle extension and within the casings, spur toothed pinions rotatably mounted on spindles extending from bearings formed in the casing and bevel toothed wheels and pinions forming a driving connection between the main driving shaft and the spur toothed pinions.
7. In a paper drying machine the combination with a drier roll and its spindle, of peripherally toothed spur gear fixed to one end of the spindle and having a diameter less than that of the roll, a casing carried by the spindle and enclosing said spur gear, a spindle journaled in said casing, a peripherally toothed spur gear carried by the spindle and meshing with the spur gear of the roll spindle, a drive shaft extending through said casing and a drive connection between said drive shaft and the second mentioned spur gear including intermeshing beveled pinions.
8. In a paper drying machine of the type in which the drying rolls are arranged in upper and lower rows with the rolls of one row staggered with respect to the rolls of the remaining row, the provision of a relatively large drive gear attached to the spindle of each roll and made of a diameter less than that of the roll, a gear casing carried by each roll spindle and enclosing the drive gear attached to said spindle, the said gear casing of each upper roll being connected to the corresponding casing of the adjacent lower roll by an intermediate casing, a drive shaft extending longitudinally from end to end of the machine between the two rows of rolls and passing through said intermediate casings, spindles journaled in each of said intermediate casings at opposite ends thereof, spur gears carried by said spindles and meshing with the spur gears of the adjacent upper and lower roll spindles, and a beveled pinion drive between the drive shaft and the second mentioned spur gears.

In witness whereof, I have hereunto set my hand.

BERNARD A. MALKIN.
